UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

COMPRESSOR-UNLOADING MECHANISM.

Application filed December 31, 1923. Serial No. 683,615.

This invention relates to compressor unloading mechanism, and more particularly to means for controlling the same.

It has for its object to provide an improved means for controlling the unloading of the compressor. A further object is to provide an improved automatic means for controlling the unloading of the compressor. Another object is to provide an improved means for controlling the unloading of the compressor by speed responsive means. A still further object is to provide improved means whereby the compressor will be unloaded until the compressor engine is brought up to speed. It is also an object of the invention to control the unloading of the compressor by a fluid used in normal operation of the compressor or engine therefor. Another object is to provide improved controlling means of the hydraulic type which uses the cooling water for the compressor engine as the controlling fluid. It is another object of my invention to provide improved means whereby a usual and necessary accessory for the compressor engine is used for controlling the unloading of the compressor. Another object is to provide improved means whereby the compressor will be unloaded while the motor is being brought up to speed and will also automatically be unloaded when a predetermined pressure in a receiver has been reached.

In the accompanying drawings I have shown for purposes of illustration one form which my invention may assume in practice.

In these drawings,—

Fig. 1 is a side elevation of the whole device.

Fig. 2 is an enlarged side elevation of a controlling valve and means for actuating the same, parts of which are shown in section and other parts broken away to facilitate illustration.

Fig. 3 is a detail sectional view through the inlet valve and unloading mechanism of one cylinder.

Fig. 4 is an enlarged central vertical section through a portion of the mechanism shown in Fig. 2.

I propose to use my improved means for controlling unloading mechanism of a compressor 1 actuated by any suitable means, herein shown as a reciprocating engine 2, both of which are mounted upon a portable frame 3 having wheels 4. Disposed on the front end of the frame 3 is a usual cooling

radiator 5 having communication as by pipes 6 and 7 with the cooling jackets 8 of the compressor engine and a circulation pump 9, respectively. The pump 9 can be of any standard type, herein shown as of the propeller type, adapted to receive an inflow of fluid through the pipe 7 and discharge the same outwardly through a pipe 10 and into the cooling jackets 8 through a reduced bushing 11. The cooling fluid can thus flow from the cooling jackets as by pipe 12 to the cooling jackets 13 of the compressor and back again to the engine as by a pipe 14 and thence into the cooling radiator.

In order to unload the compressor, I have conventionally shown at 15 a usual type of unloading mechanism comprising operating pistons, one of which is shown at 15^a, having operative connection with the inlet valves of the compressor one of which is shown at 15^b. Pressure fluid is conducted from a receiver 18 through pipes 17 and 16 to each piston, to actuate the same. To unload the compressor automatically, I propose to control the flow of fluid from the receiver 18 to the unloading mechanism 15 by two automatic devices arranged in parallel. One of these is a pilot valve 19 of the well known Judson type. Another of these is a control which is made responsive to the pressure generated by the circulation pump 9, and to accomplish this a pipe 20 communicates at one end with the pipe 10 intermediate the pump 9 and reducing bushing 11 and at its opposite end with a chamber 21 formed in a hollow casing 22. Attached to a spring pressed diaphragm 23 disposed within the chamber 21 is an actuating rod 24 which projects outwardly through the casing 22 and is connected to a lever arm 25 as by a pin and slot connection 26. One end of the lever 25 pivots about a fixed point 27, the pin and slot connection 26 being considerably closer to this end than to the other. The latter end of the arm 25 is connected by a pin and slot connection 28 to a valve actuating arm 29. The arm 29 is mounted upon a usual three-way valve 30 disposed in the lower end of the Judson valve 19. Any suitable gear reduction means and couplings 31 can be disposed between the motor and compressor to positively drive the latter.

In the operation of my device, assuming the motor not running, the diaphragm 23 will be pressed by its spring so as to cause the valve 30 to have the position as shown in Fig. 2,

in which case pressure fluid from the receiver 18 will be by-passed around the controlling valve 19 to the pipes 17 and 16 to hold open the inlet valves of the compressor and thereby cause the latter to be unloaded when the engine is started up. As the motor is brought up to speed, the rate of circulation of cooling water will be proportional thereto and as a result pressure will be increased within the pipe 10 due to the reducing bushing 11. It is understood, of course, that this bushing will not interfere with a normal circulation of cooling water or other circulated liquid generally used around such mechanisms. It will of course also be understood that the reducing bushing may be dispensed with, if a sufficient pressure is otherwise built up in order to accomplish my result, but it is thought desirable to use a reducing bushing in order to get a finer degree of adjustment. As pressure is built up, the diaphragm 23 will actuate the valve arm 29 to cut out the bypass around the Judson valve. When the engine is completely up to speed the bypass is completely cut out and the compressor loaded, for the pipes 16 and 17 will then be vented to the atmosphere as is usual in the operation of a Judson valve thus releasing the fluid pressure on the unloading mechanism. It is also to be noted that in case the pressure in the receiver reaches a predetermined point, it will automatically actuate the Judson valve to unload the compressor without in any way affecting the operation of the valve 30. Also when the engine is stopped, the pressure in the line 10 and 20 will be decreased and the arm 29 automatically thrown to the original position as shown in Fig. 2 as by the spring pressed diaphragm, thus permitting receiver pressure to actuate the unloading mechanism as originally described.

It will thus be seen from the operation of this device that I have provided an extremely simple means for controlling the unloading of the compressor due to the fact that I use the usual and necessary elements of an engine and that by a few pipe connections and other small items I can readily attach my improved means to any standard engine and compressor outfit having an unloading mechanism, it being unnecessary in any way to provide special speed responsive devices, thus reducing the initial cost of the outlay to a minimum. I can also place my diaphragm in any position convenient for the operation of the Judson valve 19 without any trouble at all for the pipe 20 may be bent to pass into any close quarters, whereas, if a mechanically actuated device were used, special linkages and supporting elements would be necessary.

While I have in this application specifically described one form which my invention may assume in practice, it will be understood that this form of the same is shown for purposes

of illustration and that the invention may be modified and embodied in various other forms without departing from its spirit or the scope of the appended claims.

What I claim is new and desire to secure 70 by Letters Patent is:

1. The combination comprising a compressor having gaseous fluid actuated unloading means, an engine for driving said compressor, means for normally circulating 75 a cooling liquid for said engine the pressure of which increases with the speed of said engine, and means whereby said liquid controls actuation of said unloading means.

2. The combination comprising an engine having circulating means for a liquid usually associated therewith, a compressor having unloading means including fluid pressure controlled devices confined in their control solely to said compressor and movable 85 to effect substantially instantaneously complete unloading on fluid pressure flow relative thereto, and means whereby said unloading means is controlled by said circulating means.

3. The combination comprising a compressor, a motor therefor, a liquid pump driven thereby, unloading mechanism for said compressor, means whereby the same is actuated by fluid pressure to effect its unloading operation including a pilot valve for controlling said unloading means, and means for controlling said valve by the liquid associated with said pump.

4. The combination comprising a compressor having unloading mechanism, a receiver, a pilot valve responsive to receiver pressure for automatically unloading said compressor when a predetermined pressure in said receiver is reached, and means for automatically bypassing said pilot valve to unload said compressor when the same is stopped.

5. The combination comprising a compressor having unloading mechanism, a receiver, a pilot valve responsive to receiver pressure for automatically unloading said compressor when a predetermined pressure in said receiver is reached, and fluid pressure actuated means for automatically bypassing said pilot valve to unload said compressor when the same is stopped.

6. The combination comprising a compressor having unloading mechanism, a receiver, a pilot valve responsive to receiver pressure for automatically unloading said compressor when a predetermined pressure in said receiver is reached, and hydraulically actuated means for automatically bypassing said pilot valve to unload said compressor when the same is stopped.

7. The combination comprising a compressor having unloading mechanism, a receiver, a pilot valve responsive to receiver pressure for automatically unloading said compressor when a predetermined pressure in

- said receiver is reached, and means for automatically bypassing said pilot valve to unload said compressor until the same is brought up to normal speed.
5. 8. The combination comprising a compressor having unloading mechanism, a receiver, a pilot valve responsive to receive pressure for automatically unloading said compressor when a predetermined pressure in said receiver is reached, and means for automatically bypassing said pilot valve to unload said compressor, said means including a hydraulically actuated member, the fluid for which is circulated in said compressor.
10. 9. The combination comprising a compressor having unloading mechanism, a receiver, a pilot valve responsive to receiver pressure for automatically unloading said compressor when a predetermined pressure in said receiver is reached, and means for automatically bypassing said pilot valve to unload said compressor, said means including a hydraulically actuated member and means, which is normally operative in circulating a supply of fluid, adapted to control said hydraulically actuated member.
15. 10. The combination of a compressor having a pressure fluid actuated unloader, a receiver, valve means for controlling flow of actuating fluid from said receiver to said unloading means to unload said compressor and for venting the fluid to the atmosphere to permit loading of said compressor, a pressure fluid actuated means for controlling said valve, and a usual liquid circulation system for said compressor, said latter means being automatically controlled by said liquid circulation system.
20. 11. The combination comprising a compressor having unloading mechanism, a receiver, means for automatically actuating said unloading mechanism when a predetermined pressure in said receiver is reached, said means including a pilot valve between said receiver and unloading mechanism, a liquid pump driven by said engine whereby the pressure of the liquid pumped is proportional to the speed of the engine, a second valve for controlling fluid flow from said receiver to said unloading mechanism, and means for actuating said latter valve by said liquid pressure to effect loading of said compressor.
25. 12. In combination, a compressor, means movable to effect unloading thereof, a source of power medium, said means operable by said power medium, power medium transmitting means connecting said first mentioned means and said source including portions arranged in parallel, and speed responsive means controlling transmission in one of said portions and pressure responsive means controlling said other portion.
30. 13. In combination, a compressor, discharge pressure controlled unloading means therefor comprising fluid operated means movable to effect unloading and discharge pressure controlled means controlling fluid supply thereto, and compressor speed controlled means for controlling fluid supply to said fluid operated means whereby said compressor may be started unloaded.
35. 14. In an unloader mechanism for compressors comprising a valve, the combination of a piston for moving the valve to effect unloading, and controlling means for said piston including two independently controlled valve means, one discharge pressure controlled and the other controlled by the speed of the compressor.
40. 15. In combination, a prime mover, a compressor driven thereby, unloading means for said compressor, a receiver for said compressor, means responsive to the speed of the prime mover for controlling said unloading means, and means responsive to the pressure in said receiver independently of the speed of the prime mover for controlling said unloading means.
45. 16. In combination, a prime mover, a compressor driven thereby, a receiver, unloading means for said compressor, and a plurality of controls for said unloading means, one of said controls being responsive to the speed of the prime mover and another being responsive to receiver pressure independently of the speed of the prime mover.
50. 17. In combination, a prime mover, a compressor driven thereby, a receiver, loading and unloading means for said compressor having a servo-motor, and a plurality of controls for the operation of said servo-motor, one of said controls being responsive to the speed of the prime mover to cause the servo-motor to actuate the loading and unloading means and another being responsive to receiver pressure independently of the speed of the prime mover to cause the servo-motor to actuate the loading and unloading means, said controls having common means for returning the servo-motor to initial position when the controls assume their initial position.

In testimony whereof I affix my signature.
CHARLES F. OSGOOD.
